Marvin Reing

UNITED STATES PATENT OFFICE

EMIL SCHEIBNER, OF PATERSON, NEW JERSEY

PERMUTATION PADLOCK

Application filed December 22, 1928. Serial No. 327,820.

This invention relates to locks of the permutation type in which a plurality of apertured discs, arranged upon an axis common to all, control the movement of a spindle 5 slidable therethrough, the present design being used in connection with the releasing mechanism of the shackled element of a padlock.

On such locks the liability of loss of a key 10 is avoided because none is used; furthermore a greater degree of security is attained as the lock bar cannot be released except by persons familiar with the combination at which the discs are set, and each disc is capable of being changed so that a wide range 15 of combinations may be made.

The foregoing advantageous object, together with others, such as compactness, simplicity and ease of operation are accomplished by the novel construction, combination and arrangement of parts as hereinafter described and illustrated in the accompanying drawing, constituting a material component hereof, and in which:—

25 Figure 1 is a sectional view of an embodiment of the invention, shown in locked position.

Figure 2 is an edge view of the lock.

Figure 3 is a transverse sectional view 30 taken on line 3—3 of Figure 1.

Figure 4 is a partial side elevational view of the lock.

Figure 5 is an expanded view showing in perspective certain of the discs and spindle.

35 Figure 6 is a side elevational view of one of the permutative sockets as removed from a disc.

The body 10 of the lock is rectangular in profile and narrow in cross section, curved 40 at its outer longitudinal edge, square in its opposite edge which contains two spaced apart openings 11 and 11', the same being receptive of the ends of a shackle 12.

Within the body is a chamber 13 with 45 which the openings 11—11' communicate and on one side of the openings are recesses 14 and 14' into which levers 15 and 15' extend, these levers being pivoted on pins 16 and 16' in the walls of the chamber 13.

50 The levers 15—15' have lock elements

17—17' adapted to engage in notches 18—18' in the entered ends of the shackle bolt 12 and are pressed into engaging positions by springs 19—19' disposed in the recesses 14—14'.

55 Passing through the inner shorter ends of the levers 15—15' is a rod 20 on which are fixed collars 21—21' in contact with the levers, the rod drawing the collars thereagainst by a coiled tension spring 22, one of its ends being fixed to a projection on the rod 20 and the other attached to a lug 23, which, with the casing end, acts to support and guard the rod.

60 The outer, rounded edge of the body 10 is machined to present a plurality of equally spaced uniform parallel slots 24^a—24^b—24^c—24^d—24^e—24^f suited to receive discs 25^a—25^b—25^c—25^d—25^e—25^f, having on their circumference numerals reading from 0 to 9, 70 inclusive, these discs containing axial bores as at 26.

65 These several bores have polygonal recesses 27 in one side of the discs and fitted to enter therein are correspondingly shaped flanges 75 27' extending from sleeves 26' adapted to enter the disc bores.

70 Each sleeve contains a key-way as 28, through which may be passed a pin as 29^a—29^b—29^c—29^d—29^e—29^f, all being fixed in a straight row in a spindle 30 having an extending knobbed head 31.

75 The spindle passes into the body from one of its end edges to have threaded upon it the several sleeves, the inner, reduced end of the spindle having a bearing in an inreaching lug 32, its extremity making contact with the longer end of a lever 33, pivoted at 34, within the chamber 13, the shorter end of the lever being pivoted at 35 to the inner end 90 of the rod 20.

80 From the foregoing it will be seen that the shackle 12 may be entered and engaged within the lock at any time quite irrespective of the position of the discs or pins on the spindle, the springs 19—19' yielding to permit such engagement.

85 However, in order to release the shackle 12 the detent levers 15—15' must be retracted which is accomplished by the pull spring 22 100

when the spindle 30 is drawn slightly outward.

Obviously the spindle can not be retracted unless all of the several sleeves are so positioned as to cause alinement of their slots or keyways, obtained by turning the discs into a known position ascertained by their numerals and as each disc is capable of several permutations by changing the position of the sleeves therein, a vast variety of new combinations may be obtained.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:—

24. 1. In a padlock the combination with a body, of a shackle having notched ends adapted to enter said casing, spring pressed detents engageable with said ends when entered, a spring drawn single rod to release said detents, a lever opposed to the rod spring, a spindle slideable and rotatable in said body to release said lever, a plurality of permutation discs rotatable in said body, sleeves in said discs through which said spindle passes, and means co-operative between said spindle and sleeves to control the sliding motion of the spindle.
25. 2. In a padlock the combination with a body, of a shackle having notched ends adapted to enter the casing, spring pressed detents engageable with said ends when entered, means to disengage said detents, a spindle controlling said disengaging means, a plurality of independently rotatable permutation discs centered on said spindle, sleeves adjustable in the discs intervening the spindle, said sleeves having slots, and pins fixed in the spindle to pass through the sleeve slots when alined by rotation of said discs.

In witness whereof I have signed my name to this specification.

EMIL SCHEIBNER.
